DESIGN FOR A SPAT

Paul J. McClure, Gloversville, N. Y.

Application April 13, 1936, Serial No. 62,090

Term of patent 14 years

To all whom it may concern:

Be it known that I, Paul J. McClure, a citizen of the United States, residing at Gloversville, county of Fulton and State of New York, have invented a new, original, and ornamental Design for a Spat, of which the following is a specification, reference being had to the accompanying drawing, forming a part thereof.

Fig. 1 is a perspective view of my spat partially open;

Fig. 2 is a fragmentary front view of the upper portion of the spat when closed.

The spat has a hookless fastener at the front thereof and is characterized in that the fastener is covered with fabric of the same color as the body of the spat so that in appearance it simulates the usual seam found in spats which are secured by buttoning or otherwise along the sides.

The sides of the spat are two continuous pieces of fabric so that when the top of the spat is concealed by the trousers, the spat appears, unless examined closely, to be a substantially continuous structure with seams only at the front and back.

I claim:

The ornamental design for a spat as shown and described.

PAUL J. MCCLURE.
